CLAIM

The ornamental design for a fish soap, as shown and described.

DESCRIPTION

FIG. 1 is a front perspective view of the fish soap of the present invention showing my new design;

FIG. 2 is a left side elevational view thereof;

FIG. 3 is a front elevational view thereof; and,

FIG. 4 is a right side elevational view thereof.

The surface or portions of the article not shown in the drawing form no part of the claimed design.
